[57] CLAIM

The ornamental design for an eyelash curler, as shown and described.

DESCRIPTION

FIG. 1 is a perspective view of an eyelash curler showing my new design;

FIG. 2 is a front elevational view thereof;

FIG. 3 is a side elevational view thereof;

FIG. 4 is a top plan view thereof;

FIG. 5 is a front elevational view thereof showing a spare resilient member held in position with a clip member; and

FIG. 6 is a cross-sectional view of the spare resilient member clipped in position and taken along lines 6—6 of FIG. 5.
